TELEVISION AERIAL SUPPORT FOR HOUSE TRAILERS

Walter C. Martin, Rte. 1, Box 476A,
Casa Grande, Ariz. 85222

Filed Oct. 10, 1972, Ser. No. 296,036

Term of patent 14 years

Int. Cl. D14—03

U.S. Cl. D26—14 F

FIG. 1 is a top perspective view of a television aerial support for house trailers showing my new design; and

FIG. 2 is an enlarged bottom perspective view thereof with the extension rod removed.

I claim:

The ornamental design for a television aerial support for house trailers, as shown.
